UNITED STATES PATENT OFFICE.

JOHN WESLEY FREEMAN, OF DENVER, COLORADO, ASSIGNOR OF ONE-HALF
TO SILAS B. A. HAYNES, OF DENVER, COLORADO.

COMBINATION DOOR KNOB AND BELL.

SPECIFICATION forming part of Letters Patent No. 700,488, dated May 20, 1902.

Application filed June 17, 1901. Serial No. 64,919. (No model.)

To all whom it may concern:

Be it known that I, JOHN WESLEY FREEMAN, a citizen of the United States, residing at Denver, in the county of Arapahoe and State of Colorado, have invented a new and useful Combination Door Knob and Bell, of which the following is a specification.

The invention relates to improvements in combination door knobs and bells.

10 The object of the present invention is to improve the construction of door-knob bells, more especially the manner of mounting the bell-ringing mechanism, and to enable the same to be readily applied to and removed from a door-knob.

The invention consists in the construction and novel combination and arrangement of parts hereinafter fully described, illustrated in the accompanying drawings, and pointed 20 out in the claims hereto appended.

In the drawings, Figure 1 is a longitudinal sectional view of a combination door knob and bell constructed in accordance with this invention. Fig. 2 is an end elevation, the 25 outer section of the inner knob being removed. Fig. 3 is a sectional view on the line 3-3 of Fig. 1. Fig. 4 is a detail perspective view of the bell-ringing mechanism.

Like numerals of reference designate corresponding parts in all the figures of the drawings.

1 and 2 designate inner and outer door-knobs connected by a hollow spindle 3, through which passes a shaft 4, which is adapted to 35 be rotated from the exterior of a door to ring the bell formed by the inner knob. The knobs are secured to the spindle by clamping-screws in the ordinary manner, and the hollow spindle is preferably provided with a removable plate 5, forming one of its sides and extending its entire length to facilitate assembling and removing and constructing the parts; but any other form of hollow spindle may be employed, if desired. The clamping- 40 screws 6 and 7 of the inner and outer knobs engage the spindle and hold the removable plate thereof in position.

The inner knob is composed of inner and outer sections 8 and 9, the inner section forming 45 a bell and provided at its inner face with a projection 10, arranged to be engaged by a

pair of disks or clappers 11, which are mounted on a rotary bar or hammer 12. The disks or clappers are provided with openings 13, receiving pins 14 of the rotary bar or hammer 55 and retained on the said pivots or pins by plates 15, secured to the outer ends of the latter, as clearly illustrated in Fig. 1 of the accompanying drawings. When the bar or hammer is rotated, the disks or clappers are 60 thrown outward by centrifugal force and strike the projection of the inner bell-section of the inner knob and sound the same. The rotary bar or hammer is rigidly secured to a pinion 16, which meshes with a gear-wheel 17, 65 and the latter carries a pinion 18, which meshes with a centrally-arranged gear-wheel 19 of the shaft 4, and when the latter is rotated by the means hereinafter described motion is communicated through the train of gears to 70 the rotary bar or hammer. The hammer and the gearing are mounted on a plate or disk 20, having a threaded stem 21, which engages interior screw-threads of the sleeve 22 of the inner section of the inner door-knob. A supporting bar or bracket 23 is secured to the 75 plate or disk and is provided at its ends with lugs or enlargements 24, which offset its central portion from the disk or plate to provide a space for the centrally-arranged gear-wheel 80 19 of the shaft 4. The gear-wheel 17 and the pinion 18 are mounted on a pivot 25, which is supported by a triangular brace 26, secured at its angle to the pivot or spindle 25 and having its end attached to the ends of the 85 bracket or bar 23 by the fastening devices 27, which secure the same to the disk or plate 20. The brace 26 is spaced from the bracket or bar by means of sleeves or washers 28 to offset it from the eccentrically-arranged gear-wheel, which meshes with the eccentrically-arranged pinion at the outer face of the transversely-disposed bracket or bar. The disk or plate 20 is provided with a perforation adapted to receive a suitable tool for enabling it to be rotated to screw its stem into and out of the threaded portion of the sleeve 90 of the inner knob. The centrally-arranged pinion and the rotary hammer are mounted on a pivot or spindle 29 of a central longitudinal support 30, which is rigidly secured to the center of the bracket or supporting-bar 95 100.

and which is provided at its outer end with a threaded socket 31 for the reception of a screw 32 for securing the outer section of the inner knob to the support 30. The spindle 29 is rigidly mounted in a perforation of the transverse bar or bracket, and the periphery of the outer section of the inner knob is spaced from the inner section of the same.

The outer end of the shaft 4 extends through the outer knob and is threaded for the reception of a head or thumb piece 33, which abuts against a sleeve 34 and which is adapted to be rotated to ring the bell. The sleeve 34 is interiorly threaded, and it is adapted to be adjusted longitudinally of the threaded portion of the shaft, and it forms a stop for the head or thumb piece 33.

It will be seen that the combination door knob and bell is exceedingly simple and inexpensive in construction, that it is adapted to be readily applied to a door, and that the parts may be readily separated and assembled.

What I claim is—

1. In a device of the class described, the combination with the inner and outer knobs and a hollow spindle connecting the same, of a shaft extending through the hollow spindle and projecting entirely through the outer knob and having the threaded outer portion, the exterior rotary thumb-piece 33 having a threaded opening receiving the threaded portion of the shaft, the threaded sleeve 34 arranged on the threaded portion of the shaft within the outer knob and extending through the same and abutting against and forming a stop for the exterior thumb-piece, and bell-ringing mechanism connected with the shaft and operated by the same, substantially as described.

2. In a device of the class described, the combination with inner and outer knobs and a connecting-spindle, of a plate arranged within and detachably secured to the inner knob, a bracket mounted on the plate and provided with an opening, a central gear-wheel arranged in the opening, a shaft secured to the central gear-wheel and extending to the outer knob and provided with means for ro-

tating it, an eccentrically-arranged spindle or pivot, a rotary hammer provided with a central pinion, an eccentrically-arranged gear-wheel meshing with the central pinion and provided with a pinion meshing with the central gear-wheel, and a brace supporting the pivot or spindle, substantially as described.

3. In a device of the class described, the combination of the inner knob composed of inner and outer sections, the inner section having its sleeve interiorly threaded, a plate provided with a threaded stem engaging the said sleeve, a bracket mounted on the plate and having an opening, a support secured to the bracket and supporting the outer section of the inner knob and provided with a pivot or spindle, a hammer mounted on the pivot or spindle, a gear-wheel arranged in the opening of the bracket, gearing connecting the pinion and the said gear-wheel, and a shaft connected with the gear-wheel, substantially as described.

4. In a device of the class described, the combination of the inner and outer sections of the inner knob, the plate detachably secured to the inner section, the bracket mounted on the plate, the longitudinal support secured at its outer end to the outer section of the inner knob and provided at its inner end with a pivot centrally secured to the bracket, a rotary hammer mounted on the pivot, a centrally-arranged gear-wheel arranged within the bracket, an eccentrically-arranged pivot or spindle, an eccentrically-arranged gear-wheel having a pinion meshing with the centrally-arranged gear-wheel, a pinion carried by the hammer and meshing with the eccentrically-arranged gear-wheel, and the triangular brace mounted on the bracket and supporting the pivot or spindle, substantially as described.

In testimony that I claim the foregoing as my own I have hereto affixed my signature in the presence of two witnesses.

JOHN WESLEY FREEMAN.
